[57] CLAIM

The ornamental design for a bottle carrier, as shown.

DESCRIPTION

FIG. 1 is a perspective view of a bottle carrier showing my new design;

FIG. 2 is a top view thereof;

FIG. 3 is an end view thereof;

FIG. 4 is a sectional elevation view, taken from one end of the bottle carrier, along line 4—4 in FIG. 2;

FIG. 5 is a bottom view thereof;

FIG. 6 is a side elevational view thereof; and

FIG. 7 is a sectioned elevational view taken in the plane 7—7 in FIG. 2.
